UNITED STATES PATENT OFFICE.

THOMAS NEWELL, OF WATERBURY, CONNECTICUT, ASSIGNOR TO AMERICAN PIN COMPANY, OF WATERVILLE, CONNECTICUT, A CORPORATION OF CONNECTICUT.

CURTAIN-ROD ORNAMENT.

No. 857,658.

Specification of Letters Patent.

Patented June 25, 1907.

Application filed June 23, 1906. Serial No. 323,169.

To all whom it may concern:

Be it known that I, THOMAS NEWELL, residing in the city of Waterbury, State of Connecticut, have invented certain new and useful Improvements in Curtain-Rod Ornaments, of which the following, taken in conjunction with the accompanying sheet of drawings, is a full and true specification.

This invention relates to end ornaments for curtain rods and similar devices, and aims to provide an improved and simplified means whereby said ornaments may be rigidly but removably attached to their rods; and the invention consists in the combination with the shell of the ornament of an expandible rod clamping tube, supported within the same in a simple manner which will be hereinafter fully described, and which will also be observed to involve the least possible number of manipulations in its manufacture.

Referring to the accompanying sheet of drawings, Figure 1 is a central section of a ball ornament containing this invention; Fig. 2, is a sectional view on line II-II of Fig. 1; Fig. 3 is a modified form of the invention applied to a different style of ornament; and Fig. 4 is a section on line IV-IV of Fig. 3.

The body of the shell shown in Figs. 1 and 2 is made of two separate parts, the part indicated by 1 being joined to that indicated by 2, by means of an ordinary seam so as to form a substantially spherical body. An opening is made or left in one of the members of the shell for the reception of the end of the curtain rod. The interior tube, designated 3, is of a length substantially equal or slightly longer than the diameter of the shell, and is confined within the shell with one end seated firmly against the inner concave wall thereof, opposite the curtain rod opening, while the other end is secured to the margin of said opening by means of the inturned flange 4 thereof. The tube 3 is split longitudinally as shown and is also slightly tapered toward its inner end so that it may expand when the curtain rod is thrust into it.

The curvature of the wall of the shell is sufficient to hold the end of the tube properly in central position within the shell, but is not so great as to prevent the slight expansion of the said end when the tube has to adapt itself to the relatively larger diameter of the curtain rod. The pressure of the tube

against the concave wall serves to increase its natural elasticity, and by proper adjustment of said pressure in the first instance, a split tube of comparatively thin stock may be made to have a firm and positive grip upon the rod. The pressure of the tube against the shell is, of course, brought about by the connection of the tube at the curtain rod opening, the tube being of sufficient length to reach the concave wall as above described.

In Figs. 3 and 4 the body of the shell consists of a hollow body which is crimped horizontally so as to give a fancy appearance. In this form of ornament, there is an opening at both ends and the split tube 3 bears with one end against the concave wall adjacent one of said openings and is secured in this position by means of two annular flanges, designated 5 and 6, which are formed on the said tube and located respectively on opposite sides of the margin of the other opening. The end of the tube protrudes slightly from the shell as shown and the two flanges are pressed firmly together so as to clasp the crimped margins of the opening and thereby hold the tube in position and prevent its withdrawal. The opening in the shell adjacent the inner end of the tube may be closed by further ornamentation if desired, and the extent to which the free end of the tube projects from the shell may be varied as desired. When the curtain rod is pushed into the tube, it is clasped by it and the ornament is firmly held in proper alignment with the rod.

It will be understood that the invention is not limited to the specific form of ornament as herein illustrated, but that the invention may be applied in obvious manner to a great variety of ornamental rod terminals.

Having described my invention, what I claim and desire to secure by Letters Patent of the United States is

1. A curtain rod ornament consisting of a hollow shell having an opening therein and an expandible hollow supporting tube inside said shell adapted to bind on the curtain rod, one end of said tube being secured to the shell adjacent said opening and the other being seated against the opposite wall of said shell.

2. A curtain rod ornament consisting of a hollow shell having an opening therein for

the reception of the curtain rod, and provided, opposite said opening, with an interior concave wall, in combination with a split tube adapted to receive the aforesaid 5 curtain rod within the shell, said tube being secured at one end to the shell at a point adjacent the said opening and having its other end seated against said concave wall, the curvature of said wall being sufficient to hold 10 the said end in central position and not so great as to prevent a slight expansion of said split tube in accommodating itself to the curtain rod.

3. A curtain rod ornament consisting of a 15 substantially spherical hollow shell having an opening therein, in combination with a split rod-clamping tube adapted to receive the end of the curtain rod thrust therein, inside said shell, having one end located adjacent to and surrounding the said opening, and the other end seated against the inner wall of said shell, diametrically opposite from said opening.

4. A curtain rod ornament consisting of a 25 hollow shell having an opening therein, and formed with an inner concave wall opposite said opening in combination with an interior rod-clamping tube having one end seated against said concave wall and provided near 30 its other end with flanges embracing the

margin of said opening to hold said tube in position.

5. A curtain rod ornament consisting of a hollow shell having an opening therein for the reception of the rod, and a rod-clamping 35 tube having one end seated against the inner wall of said shell and provided with annular flanges formed upon it and respectively located on opposite sides of the margin of said opening to hold the end of said tube in contact with said inner wall of the shell. 40

6. A curtain rod ornament comprising a hollow shell having an opening therein to receive the rod, in combination with a split tube having one end seated against the inner 45 concave wall of said shell and the other extending through said opening and means for securing said tube within said opening to prevent its withdrawal from the said inner wall, said tube being adapted to removably hold 50 the end of a curtain rod thrust into the aforesaid opening in the shell.

In testimony whereof, I have signed my name to the specification in the presence of two subscribing witnesses.

THOMAS NEWELL.
